To all whom it may concern:

Be it known that I, Tora Coleman, a citizen of the Republic of Latvia, residing at No. 301 East 38th Street, city of New York, county of New York, and State of New York, have invented a new, original, and ornamental Design for a Dress, of which the following is a specification, reference being had to the accompanying drawing, forming a part thereof.

The characteristic feature of the design consists of a dress with raglan sleeves having a pleated panel attached adjacent each shoulder, said panels crossing over at the waist and attached thereto and hanging loosely from the waist down as shown.

I claim:

The ornamental design for a dress, as shown and described.
